UNITED STATES PATENT OFFICE.

EDWIN A. RIVES, OF GREENSBORO, NORTH CAROLINA, ASSIGNOR OF ONE-FOURTH TO
GEORGE W. NEISTER, OF GREENSBORO, NORTH CAROLINA.

CAR DOOR.

Application filed April 13, 1923. Serial No. 631,829.

To all whom it may concern:

Be it known that I, EDWIN A. RIVES, a citizen of the United States, residing at Greensboro, in the county of Guilford and 5 State of North Carolina, have invented certain new and useful Improvements in Car Doors, of which the following is a specification.

This invention relates to car doors and 10 has for its object the provision of novel, simple and inexpensive means for moving a freight car door from open to closed position or vice versa, which will operate easily and without requiring excessive exertion 15 upon the part of the workmen. Another object of the invention is to provide a structure in which the door will be effectually prevented from swinging laterally relative to the car, and another object of the invention 20 is to provide means whereby the door may be secured in either the closed or the open position. Other incidental objects of the invention will appear in the course of the following description.

25 The invention is illustrated in the accompanying drawings, in which

Figure 1 is a side elevation of a portion of a car having my improved door mounted thereon and shown in the closed position;

30 Fig. 2 is a similar view showing the door in the open position;

Fig. 3 is a transverse section on the line 3-3 of Fig. 1;

Fig. 4 is an enlarged detail section on the 35 line 4-4 of Fig. 1, and

Fig. 5 is a side elevation showing a slight modification.

In the drawings, the reference numeral 1 indicates a portion of a car having a door opening 2 in its side, the said opening being 40 formed in the usual or any preferred manner. Upon the door jambs 3 at the upper ends thereof, I secure brackets 4 in which are secured rigidly the ends of a track rod 45 5 which is preferably circular in cross section, as shown most clearly in Fig. 4. To the lower bar 6 of the car frame, I secure a guard rail 7 which is disposed in spaced relation to the said frame bar 6 and may be 50 constructed at its ends with inclined depending extensions 8 having openings 9 therethrough for a purpose which will presently appear. Supported by and between the guard rail 7 and the car frame or body are rollers 10 which may be provided in any

preferred number and constitute supports for the door, indicated at 11. The door is of the usual form consisting of upright planks or boards secured to braces 12 in order to attain the proper strength and 60 rigidity, and upon the outer side of the door at the upper end thereof I secure brackets 13 which are offset at their upper ends, as shown at 14, whereby they may clear the track bar 5, as shown clearly in Fig. 4. Between the upper extremities of the said brackets and the upper end of the door, I mount rollers 16 upon pintles 17, the said rollers being adapted to travel upon the track bar 5 and thereby support the door 70 for easy movement, as will be readily understood. It will be seen at once that the described arrangement provides rotatable or rolling supports for the door at both its upper and lower ends so that it will move 75 easily when it is to be opened or closed, and it is to be noted that the lower edge of the door is disposed between the guard rail 7 and the side of the car, as shown clearly in Fig. 3, so that the door cannot swing outwardly laterally from the car. I thus remove the cause of frequent accidents which tear the door from the car, and I also prevent the door being pried outwardly at its 80 lower end without breaking the seal. The latter practice is frequent with thieves or mischievously inclined persons and has enabled trespassers to extract freight from a car without breaking the seal so that the loss was not discovered until, in many instances, apprehension of the thieves was impossible. Upon the lintel 18, at the center of the same, I pivotally secure the upper end of an operating lever 19 which is mounted to swing in a plane parallel with the 85 plane of the door, as will be readily understood upon reference to the drawings. This lever is long enough to extend to a point below the guard rail 7 and is constructed 90 between its ends with a longitudinal slot 20 in which is engaged a stud or pin 21 carried by a bracket 22 secured upon the door, as shown. The lower free end of the lever is provided with an opening 23 therethrough 95 which may align with the opening 9 through either extension 8 of the guard rail, and receive a sealing device 24 whereby the door may be locked in its closed position. When the door is open, any convenient pin or tool 100 may be inserted through the aligned openings 105 110

23 and 9 and thereby prevent premature closing of the door. The lever is also equipped adjacent its lower end with an eye or ring 25 in which is engaged or to which 5 is attached one end of a chain 26, and upon the side of the car beyond the ends of the guard rail, I secure similar rings or eyes 27. The chain is equipped at its free end with a hook 28 adapted to engage in a link of 10 the chain or in the eye or ring 25, as the case may be. When the lever is swung to the limit of its movement in either direction, the chain is passed through the adjacent eye 27 and double upon itself so that the hook 28 15 may be engaged in a link of the chain or in the eye 25, and a seal, indicated at 29 in Fig. 5, may be secured to and through the links of the chain so that opening of the door cannot be effected without breaking the 20 seal and, therefore, rendering detection certain.

In operating my improved door, it is necessary only to swing the lever about its pivot in the proper direction in order to move the 25 door from open to closed position or from closed to open position. The pin and slot connection between the lever and the door will transmit the movement of the lever to the door so that the door will be slid in a 30 rectilinear path from one end of the guard rail 7 and the track rail 5 to the opposite ends thereof and binding between the door and the lever cannot occur. When the door has been shifted, the lever may be secured 35 against return movement in the manner described. It is to be noted that the construction employed by me not only prevents the door being pried laterally from the car but is of such construction that, if the car 40 should sag from the effects of the weather upon the wood employed in the car, the door may still move easily inasmuch as the track rail 5 is secured only at its ends and, therefore, offers no obstruction to the movement 45 of the door but is so mounted that, if the door frame should sag, the track rail or bar and the supports for the lower end of the door will partake of the sagging movement so that the relative positions of the parts 50 will remain constant.

The extensions 8, in some instances, may be found somewhat objectionable inasmuch as they locate the locking points of the operating lever below the bottom of the door opening and if the car should be stopped 55 close to a loading platform, it might prove inconvenient for the attendants to reach the seals in order to open the car. I, therefore,

provide the modified or alternative construction shown in Fig. 5 in which the guard rail 60 30 is constructed without the extensions so that its lower edge throughout its extent is substantially flush with the car floor, and openings 31 for the reception of locking pins or seals are provided in the ends of the 65 guard rail proper instead of in depending extensions therefrom as in the previously described arrangement. Otherwise the form shown in Fig. 5 is identical in all respects with the construction first described and illustrated in Figs. 1 to 4.

It will be readily noted that my improved car door mounting and operating mechanism is exceedingly simple and may be readily applied to any car now in existence 75 as well as to cars which may be hereafter built. The device will operate always very easily so that the brakeman or other employee charged with the duty of opening or closing the car door may perform his duty 80 without being subjected to physical strain or being obliged to put forth any unusual exertion.

Having thus described the invention, what 85 is claimed as new is:

In a structure of the character described, a car having a door opening in one wall thereof, a door slidably mounted for movement longitudinally of the car wall into and out of a closed position, a guide strip extending longitudinally of the car wall across and beyond the lower end of said door opening and overlapping the lower end portion of said door, openings being provided in the end portions of said guide strip, an operating 90 lever for said door pivoted at its upper end to the car wall above the door opening and having its lower free end extending in overlapping relation to said guide strip and provided with an opening adapted to register 95 with the openings in the ends of said guide strip and receive a fastener, said lever having connection with the door whereby sliding movement may be imparted to the door when the lever is moved, an eye carried by 100 the free end portion of said lever, eyes carried by the car wall in spaced relation to the ends of said guide strip, and a chain carried by the eye of said lever and adapted to be passed through an eye of the car wall and having means at its free end for engagement 105 with the eye of the lever to secure the door in an adjusted position.

In testimony whereof I affix my signature.

EDWIN A. RIVES. [L.S.]
